COMBINED PEG HEAD, NECK AND FINGER
BOARD OF A GUITAR OR SIMILAR ARTICLE

Charles A. Gauvin, 805 S. Water St.,
Silverton, Oreg. 97381

Filed Nov. 15, 1965, Ser. No. 88,094

Term of patent 14 years

(Cl. D56—1)

FIG. 1 is a front elevational view of a combined peg head, neck and finger board of a guitar or similar article, showing my new design;

FIG. 2 is a left side elevational view;

FIG. 3 is a rear elevational view; and

FIG. 4 is a cross-sectional view, to an enlarged scale, taken on line 4—4 in FIG. 1.

I claim:

The ornamental design for a combined peg head, neck and finger board of a guitar or similar article, substantially as shown and described.
